CONVERTIBLE BED AND ARMCHAIR COMBINATION

Amadeu Pelliccione, Rio de Janeiro, Brazil

Application December 30, 1949, Serial No. 135,862
In Brazil May 16, 1949

2 Claims. (Cl. 155—49)

1

The present invention relates to convertible furniture and is particularly directed to an armchair which is easily and simply converted into a bed.

Many types of armchairs convertible into beds have heretofore been proposed, however, these convertible armchairs have generally been provided with fixed armrests and the conversion of such an armchair into a bed has been usually accomplished by means of complex mechanisms requiring comparatively expensive parts and being difficult to operate.

An object of the present invention is to provide an armchair which converts into a bed and is simple and inexpensive in construction as well as easy to operate.

Another object is to provide an armchair which is convertible into a bed and wherein the chair arm assembly, on which the user's forearms or elbows may rest, is swingably mounted to support a head board assembly when the armchair is converted into a bed.

The above and other objects, features and advantages of the present invention will be apparent in the following description of an illustrative embodiment thereof which is to be read in connection with the accompanying drawings forming a part hereof and wherein:

Fig. 1 is a perspective view of an armchair constructed in accordance with the present invention and shown in condition to serve as an armchair;

Fig. 2 is a perspective view of the frame of the armchair of Fig. 1 shown in an intermediate position during the conversion of that armchair into a bed; and

Fig. 3 is a perspective view of the armchair of Fig. 1 shown in condition to serve as a bed.

Referring to the drawing in detail, it will be seen that the illustrated embodiment of the invention includes a double-bottomed base 17 which is open at one end and has side members 5 extending along the opposite sides thereof. The base 17 is supported on suitable legs 21 and at its closed end is hingedly connected to the lower end of a chair back member 1, for example, by the hinges 18. The chair back member 1 is formed with a transversely extending cavity 2 in the back surface thereof and adjacent its free end. A pair of legs 3 are foldably pivoted within the cavity 2 to swing between positions nested within the cavity (Fig. 1) and positions extending from the back member 1 (Figs. 2 and 3) for supporting the latter in the plane of the base 17 when the back member 1 is lowered to provide the foot portion of a bed.

2

In accordance with the present invention, the chair arm assembly includes a pair of arm rests 11 and 12 which are connected together at one end by a cross-piece 13 to form a U-shaped assembly 10. A swingable support member 16 is provided for each of the arm rests 11 and 12. Each of the support members 16 is fixed at one end to the related arm rest adjacent the end of the latter remote from the cross-piece 13, and at its other end each support member 16 is pivotally mounted on the related side member 5 adjacent the open end of the base 17. A stop member 6 is secured to the inner side of each of the support members 16 and is formed with an inclined lower edge 7a which is adapted to abut against an inclined end edge 7b formed on the related side member 5 for supporting the members 16 in vertical positions. When the support members 16 are vertically disposed, the arm rests 11 and 12 are arranged horizontally, and the cross-piece 13 is positioned in back of the chair back member 1 to hold the latter in an elevated, back forming position (Fig. 1). If desired, dowels 14 and 15 may be extended from the back surface of the chair back member 1 (Fig. 2) to underlie the cross-piece 13 when the latter is arranged to hold the member 1 in its elevated position thereby further complementing the abutting surfaces 7a and 7b in holding the arm rests 11 and 12 horizontal.

A board member 19 extends slidably into the base 17 through the open end of the latter and has an extension 20 hinged to its outer end (Fig. 2). The hinged extension 20 is foldable on top of the board member 19 for storage with the latter within the base 17. As seen in Fig. 2, the arm rests 11 and 12 are provided with stops 22 secured to the under surfaces thereof. When the chair arm assembly is pivoted to a position in which the arm rests 11 and 12 are vertically disposed (Fig. 3), the board member 19 may be withdrawn from the base 17 and its outer end supported on the stops 22. The hinged extension 20 may then be pivoted upwardly to a vertical position and rested against the vertically disposed arm rests 11 and 12 to provide a head board, as in Fig. 3.

The support members 16 are preferably fixed to the arm rests 11 and 12 at locations on the latter spaced from the ends of the arm rests remote from the cross-piece 13 so that the portions of the arm rests between said ends remote from the cross-piece and the support members 16 constitute leg members to support the members 16 in horizontal positions and with the extended board member 19 parallel to the base 17.

The convertible armchair embodying the present invention preferably includes three cushions. When the armchair is in its armchair forming condition (Fig. 2) with the arm rests 11 and 12 horizontally disposed and the cross-piece 13 retaining the back member 1 in its elevated back forming position, the board member 19 and hinged extension 20 are stored together within the base 17 and two cushions are superposed upon the base 17 to provide a seat while the remaining cushion is positioned against the back forming member 1.

In converting the armchair of Fig. 1 into a bed, the arm rests 11 and 12 are pivoted upwardly and forwardly to their vertical positions and the freed back member 1 is lowered to its horizontal position and supported on the legs 3. The board member 19 is then withdrawn from its stored position within the base 17 to form the head portion of the bed, and the extension 20 is pivoted upwardly to its position against the arm rests to provide a head board. With the various parts of the armchair frame disposed as indicated above, a cushion is disposed on each of the back member 1, the base 17 and the board member 19 to provide a mattress, as in Fig. 3.

While I have described and illustrated a particular embodiment of my invention, it is to be understood that the invention is not limited to the precise details thereof and that various changes and modifications may be made therein without departing from the scope of the invention as defined in the appended claims.

I claim:

1. A convertible arm chair to bed combination comprising a double-bottomed base open at one end, a board member slidably extending into said base through said open end of the latter and having an extension hinged to the outer end thereof, said hinged extension being foldable onto said board member for storage with the latter within said base, a chair back member hinged at the lower edge thereof to the other end of said base member to form a foot portion of a bed when swung back and down, a substantially U-shaped arm assembly including a pair of arm rests connected together at one end by a cross-piece, a swingable support member for each of said arm rests, each support member being fixed at one end to the related arm rest adjacent the end of the latter remote from said cross-piece,

means pivoting the other ends of said support members on the sides of said base adjacent said open end of the latter so that, swinging of said support members to dispose said arm rests horizontally, positions said cross-piece for engagement behind said chair back member to hold the latter in an elevated back forming position, while swinging of said support members to vertically dispose said arm rests positions the latter to support said hinged extension in a vertical position, when the latter is withdrawn from said base with said board member and unfolded relative to the latter, to thereby constitute a head board, and support members on said arm rests arranged to underlie and support said outer end of the board member when the latter is withdrawn; and said arm rests are vertically disposed.

2. A convertible arm chair to bed combination as set forth in claim 1, including elevating floor engaging legs on said base, a cavity formed in the back of said chair back member adjacent the edge of the latter remote from said hinged lower edge thereof, and foldable legs pivoted on said chair back member to swing between stored positions in said cavity and operative positions extending from said chair back member for supporting the latter when forming the foot of the bed; and wherein said support members are fixed to said arm rests at locations on the latter spaced from said ends remote from the cross-piece so that the portions of said arm rests between said ends remote from the cross-piece and said support members constitute leg members when said arm assembly is in its head rest forming position.

AMADEU PELLICCIONE.
